Primary Examiner — Barbara Fox*Assistant Examiner* — Mary C Ramirez(74) *Attorney, Agent, or Firm* — Gunn, Lee & Cave, P.C.; John C. Cave(57) **CLAIM**

The ornamental design for a security camera housing, as shown and described.

DESCRIPTION

FIG. 1 is a front perspective view of the security camera housing showing the new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines shown in the drawings illustrate portions of the security camera housing that form no part of the claimed design.
